UNITED STATES PATENT OFFICE.

WILLIAM WAKEFIELD WORCESTER, OF JEFFERSONVILLE, INDIANA.

SHOE-BRUSH.

SPECIFICATION forming part of Letters Patent No. 605,533, dated June 14, 1898.

Application filed August 19, 1897. Serial No. 648,818. (No model.)

To all whom it may concern:

Be it known that I, WILLIAM WAKEFIELD WORCESTER, a citizen of the United States, residing at Jeffersonville, in the county of Clarke 5 and State of Indiana, have invented a new and useful Brush, of which the following is a specification.

My invention relates to improvement in devices for polishing shoes, especially tan 10 shoes; and the objects of my improvement are, first, to adapt the usual and convenient form of the shoe-brush to polishing tan shoes; second, to provide a polishing device which shall be resilient, and consequently enter the 15 crevices and adapt itself to other inequalities of the surface of shoes; third, to provide an implement whose polishing fabric may be renewed, and, fourth, to provide a polishing implement which may be used as an ordinary 20 brush by removing the polishing fabric. I attain these objects by the construction shown in the accompanying drawings, in which—

Figure 1 shows a plan of a brush constructed according to my improvement, and Fig. 2 a 25 vertical longitudinal section of the same.

Referring now to the details of the drawings by numerals, 1 represents the block, in which are set rows of brushes of bristles 2, over and between which is set a convoluted cloth 3, the convolutions of which are held by 30 the wires 6, whose ends are turned down and forced into the blocks, as indicated by dotted lines in Fig. 2. The ends of the cloth are preferably fastened by tacks 4 to the blocks 1 at each end. By this arrangement the cloth 35 is held always in position in such a manner that the brush is not likely to get out of order.

What I claim as new is—

As an improved article of manufacture, a brush, provided with a series of rows of bristles 2, convolutions of fabric 3, covering said 40 bristles and wires 6, set between the rows of bristles to hold the convolutions in place, substantially as described.

WILLIAM WAKEFIELD WORCESTER.
